UNITED STATES PATENT OFFICE.

FLORE HENGYE, OF JOLIET, ILLINOIS.

DEVICE FOR RAISING SUNKEN VESSELS.

1,115,670.

Specification of Letters Patent.

Patented Nov. 3, 1914.

Application filed July 30, 1914. Serial No. 854,145.

To all whom it may concern:

Be it known that I, FLORE HENGYE, subject of the King of Hungary, residing at Joliet, in the county of Will and State of Illinois, have invented certain new and useful Improvements in Devices for Raising Sunken Vessels, of which the following is a specification.

This invention relates to improvements in devices for raising sunken vessels.

The primary object of this device is to provide a means readily attachable to a sunken vessel, and whereby the vessel may be raised to the surface of the water by means 15 of air pumped from a boat from the surface thereof, the entire apparatus being removable and of service for repeated operations.

A further object is to provide a plurality of floats including telescopic floats, all of 20 the same being inflatable and adapted to encircle a sunken vessel for the purpose of raising the same.

A still further object is to arrange a plurality of hollow bodies filled with water 25 around a sunken vessel, and to then substitute air for the water within said bodies, and thus buoying up the sunken vessel to the water surface.

With these general objects in view, and 30 others that will appear as the nature of the invention is better understood, the same consists in the novel combination and arrangement of parts hereinafter fully described and illustrated in the drawings, and pointed 35 out in the appended claims.

In the drawings forming a part of this application and in which like designating characters refer to corresponding parts throughout the several views, Figure 1 illustrates the entire device in connection with a sunken vessel upon the bottom of the ocean. Fig. 2 is a longitudinal central sectional view taken horizontally through the hull of the sunken vessel. Fig. 3 is a front elevation 45 thereof with the connecting tubes broken away. Fig. 4 is a central longitudinal sectional view of one of the telescoping floats. Fig. 5 is a side elevation of a globular float attached to the vessel, the latter being 50 broken away. Fig. 6 is a detail sectional view through the corrugated tubular telescoping float at the connection between the sections, and Fig. 7 is a detail sectional view 55 through the pipe entering portion of one of the globular floats.

Referring more in detail to the drawings a vessel 10 is illustrated as positioned upon the ocean bottom 11 and having the invention operatively attached thereto. Telescoping floats 12 are positioned longitudinally 60 at opposite sides of the vessel each consisting of tubular members 13 telescopically arranged, and whereby the chamber 14 therein may be regulated in size. The outer member of the float 12 has a water tight connection with the member received therein by means of an intermediate packing 15, while both of the sections 13 are provided with a longitudinally corrugated surface for assisting in retaining the float against the side 65 of the vessel. Each section 13 is provided with a side hook 16 adapted to enter a ring 17 which the diver who applies the floats attaches to the adjacent side of the vessel. The desired number of hollow spherical or 70 globe shaped floats 18 are provided which have a portion of their outer surfaces supplied with corrugations 19 which have centrally positioned hooks 20 adapted to be received within the rings 21, secured to the 75 side of the vessel 10 at any points thereon where it is desired to attach one of said floats. The spherical floats 18 are provided upon diametrically opposite sides with rings 22 while similar rings 23 are positioned at 80 the opposite ends of the telescoping floats 12, and whereby the floats may be positioned in spaced relations around the hull of the vessel and there secured by means of connecting chains 24. A short chain 25 is also 85 connected between the rings 23 of the sections 13 and whereby the length of the float 12 is regulated as well as the side of the air chamber 14 therein. Each of the floats 18 is provided with an air inlet pipe 26 and 90 whereby air is supplied to the said floats from the air pump 26 mounted upon the department boat 27 which carries the device and the crew of divers. A similar air inlet pipe 28 connects the pump 26 with the telescoping float 12, while each of the floats 12 and 18 are provided with outlet pipe 29, which outlet pipes are preferably formed of rubber or similar material and have open 95 outlet ends, arranged adjacent the gunwale 100 of the boat 27. With this apparatus provided upon the boat 27 the boat is moved to a position directly above the sunken vessel and the divers then position the spherical floats 18 at opposite positions adjacent both the 105 gunwale 110.

bow and stern of the vessel and also position the floats 12 at opposite sides thereof and hook the said floats to the adjacent rings upon the hull, it being noted that all of the 5 floats are so attached when the piping is disconnected therefrom and while the floats are filled with water. The chain 25 is then positioned to regulate the size of the float 12 while the chains 24 are connected between 10 the different floats to secure the floats around the side of the vessel. The inlet and outlet pipes are then connected to all the floats and whereupon an operating of the pump 26 forces air into the floats, thus driving out 15 the water contained therein through the pipe ends 30 and subsequently filling the floats with air.—The number of floats so secured to the vessel is arranged to be sufficient when filled with air to afford the required buoyancy to lift the vessel to the surface of the 20 water and float the same thereon.

While the forms of the invention herein shown and described are what are believed to be preferable embodiments thereof, it is nevertheless to be understood that minor 25 changes may be made in the form, proportion and details of construction without de-

parting from the spirit and scope of the claims.

What I claim is:—

1. A device of the class described comprising in combination spherical hollow floats, corrugated portions upon the surfaces of said floats, telescoping floats, chain connections between all of said floats, an air 35 pump, pipes connecting said pump and said floats, and outlet pipes leading from said floats and exhausting adjacent the pump.

2. A device of this class comprising telescoping tubular sections inclosing a chamber therein, water tight packings between said sections, terminal rings upon said sections, and adjustably positioned chain connecting said rings, and adapted for controlling said sections, the exterior surfaces of 45 said sections being longitudinally corrugated.

In testimony whereof I affix my signature in presence of two witnesses.

FLORE HENGYE.
